UNITED STATES PATENT OFFICE.

CHARLES EYSTER, OF HOLCOMB, ILLINOIS.

SAFE OR VAULT PROTECTION.

SPECIFICATION forming part of Letters Patent No. 642,684, dated February 6, 1900.

Application filed November 26, 1898. Serial No. 697,508. (No model.)

To all whom it may concern:

Be it known that I, CHARLES EYSTER, a citizen of the United States, residing at Holcomb, in the county of Ogle and State of Illinois, have invented certain new and useful Improvements in Safe or Vault Protection, of which the following is a specification.

The object of this invention is to protect a safe or vault by an outer casing, the combination-knob and bolt-throwing levers of the casing-door operating the connection-knob and bolt-throwing lever of the safe or vault-door.

In the accompanying drawings, Figure 1 is an isometrical representation of a safe and outer casing and a mechanism for operating the combination and bolts. Fig. 2 is a vertical section through the doors of the casing and safe. Fig. 3 is a vertical section through the doors of the casing and safe and the levers for operating the bolts. Fig. 4 is a face representation of the inner end of the lever after operating the bolts of the casing-door, showing the lever of the safe-door.

The outer casing is composed of the front 1, ends 2, top 3, and bottom 4, made up of metallic plates secured together in any suitable manner. The front has an opening 5, closed by a hinged door 6. This hinged door 10 supports a combination-knob 7 and a lever 8 for throwing the bolts 9. The shank 10 of the combination-knob 7 extends through the door and supports a sleeve 11, having a hollow center 12 and radial flanges 13. A latch 14 has a pivotal connection with the flanges 13, which 15 guide it in its movement. A plunger 15 is located in the sleeve and guided by the projection 16, moving in the groove 17, and a spring 18 holds the plunger in its outward 20 position in a yielding manner. The latch is of such form that when the plunger is in its outward position the inner end of the latch will be depressed and when the plunger is in its innermost position the outer end of the 25 latch will be depressed, as shown at Fig. 2. The lever 8 for throwing the bolt-works of the outer casing extends through the outer door, and to its projecting end is secured an extension having a slotted end 19 and depending socket composed of the end 20 and sides 21 and 22. The side 22 is shorter than the side 21. A cam 23 projects from the extension.

To the inner face of the door of the outer casing is pivoted a bail or loop 24, resting upon the cam 23.

55

Within the casing is located a safe 25, having a door 26 and the usual combination-knob 27 and bolt-throwing lever 28. The combination-knob has a lengthwise groove 29. At the front corners of the safe are located channel-bars 30, embracing the front and sides of the safe. These channel-bars are secured to the top and bottom of the outer casing in any suitable manner. A top channel-iron bar 31 embraces the front and top faces of the safe 65 and is secured to the upright channel-bars 30. Rods 32 connect the upright channel-bar with the bars 33, extending across the rear of the safe. The front face of the upright channel-bars are provided with hooked projections 34 and 35, facing each other. A bar 36, having its ends reduced to fit within the hooked projections 35, is placed across the safe-door and held within the hooked projections by the cams 37, pivoted to the upright channel-bars 70 30. Opposite the bolt-throwing lever of the safe and from the bar 36 rises a projection 38, curved in form, and to the upper face of this bar is securely fastened a spring-bar 39.

When the door of the outer casing is opened 80 and the safe-door unlocked, the parts will appear as shown at Fig. 1, and upon the removal of the bar 36 the safe-door can be opened.

In securing the doors the safe-door is closed, 85 the bar 36 placed across it, and the cams turned down over its ends. If the dials of both combination-knobs correspond, the outer end of the latch will enter the slot 29 of the knob of the safe-door, and the lever for throwing the bolts of the safe-door will be received within the depending socket of the extension secured to the bolt-throwing lever of the outer door, and as the door to the outer casing is closed the knob of the combination of the 90 safe-door will force in the plunger 15, which will cause the outer end of the latch to be depressed into the slot 29, thereby forming a connection between the knob of the outer-casing door and safe-door. In turning the 100 lever of the door of the outer casing the socket will also turn the lever of the bolt-works of the safe-door, thereby throwing the bolts of both doors and at the same time the bail 24

will be raised by the cam 23 into engagement with the hooked projections 34, and by turning the knob 7 the combination of the safe-door is thrown off, thereby locking the bolts. 5 The lever 28 in turning to throw the bolts will depress the spring 39, as shown at Fig. 4, so that the longer side 21 of the socket will pass the end of the spring. Should the safe be forced back from the upright channel-bars 10 30 and the bolt-throwing lever be freed of its engagement with the socket, the spring 39 will move in contact with the side 21 of the socket, thereby holding the bolts of the door of the outer casing thrown; also holding the 15 bail in connection with the hooked projections 34, so that the outer door will be locked after the influence of the combination controlled by the knob 27 has been withdrawn, and it will be necessary to force an entrance 20 through the outer casing in order to restore the safe to its former position. The beveled end 40 of the rear wall 20 of the extension will engage the upturned portion 38, thereby drawing the door of the outer casing firmly 25 into position, and the rear wall 20 will engage the upturned portion 38 and tend to form a connection between the door of the outer casing and the upright channel-bar.

In the latest make of safe and vault doors, 30 when the bolt-works are withdrawn the combination-knob remains stationary, and in closing the door of the outer casing, should the outer end of the latch fail to enter the groove of the knob 27, the latch will bear 35 against the conical end of the knob, and by turning the knob controlling the latch the latch may be turned until it will enter the groove, when the door may be closed, which will force in the plunger and force the outer 40 end of the latch farther into the groove.

So far as known to me I am the first to form a connection between the combination-knobs so that both combinations can be manipulated in unison, also to form a connection 45 between two sets of bolt-works, so that both will be operated together.

I have not shown all the mechanism for throwing the bolts and operating the combination, as such parts are old and form no 50 part of my invention.

It will be noticed that it is not necessary to form any permanent connection with the safe-door in the way of attachments, which will be appreciated by the owner of the safe. 55

In the drawings I have shown the rear of the safe unprotected by the outer casing, as such rear wall may be a part of the building, or the casing may extend around it.

I claim as my invention—
60 1. In a safe or vault protection, an outer door and an inner door, each provided with a dial and knob, and a movable lever, the combination-lock of the inner door controlling the movements of both levers.

65 2. In a safe or vault protection, an outer door and a movable inner door each provided

with a dial and knob and a movable lever, the combination-lock of the inner door controlling the movements of both levers.

3. In a safe or vault protection, an outer 70 door and an inner door, each provided with a dial and knob, and a movable lever, the combination-lock of the inner door controlling the movements of both levers and the outer door having auxiliary locking means. 75

4. In a safe or vault protection, an outer door and an inner door, each provided with a dial and knob, the spindle of the knob of the outer door supporting a projection and the knob of the inner door having a peripheral 80 lengthwise groove adapted to receive the projection.

5. In a safe or vault protection, an outer door and an inner door, each provided with a dial and knob, the spindle of the knob of the 85 outer door supporting a pivoted projection and the knob of the inner door having a peripheral lengthwise groove adapted to receive the projection.

6. In a safe or vault protection, an outer 90 door and an inner door, each provided with a dial and knob, the spindle of the knob of the outer door supporting a projection, and the knob of the inner door having a peripheral lengthwise groove adapted to receive the 95 projection.

7. In a safe or vault protection, an outer door and an inner door, each provided with a lever, the lever of the door provided with a socket adapted to receive the lever of the 100 door.

8. In a safe or vault protection, an outer door and an inner door, each provided with a bolt-throwing lever, the lever of the outer door provided with a socket adapted to receive 105 the lever of the inner door, and a spring depressed by the locking movement of the lever of the inner door and adapted to limit the movement of the lever of the outer door when the lever of the inner door is withdrawn. 110

9. In a safe or vault protection, an outer door, and an inner door, each provided with a bolt-throwing lever and adapted to be operated in unison, and other securing means for the outer door operated by the movement 115 of its bolt-throwing lever.

10. In a safe or vault protection, an outer door, and an inner door, each provided with bolt-throwing levers and adapted to be operated in unison, a bar extending across the face 120 of the inner door, the lever of the outer door having an engagement with the bar.

11. In a safe or vault protection, an outer door and an inner door, each provided with a bolt-throwing lever and adapted to be operated in unison, and a removable bar extending 125 across the face of the inner door, the lever of the outer door having an engagement with the bar.

12. In a safe or vault protection, an outer 130 door, a stationary support, a bail pivotally supported by the door and means for moving

it into engagement with the stationary support by the locking movement of the outer door.

13. In a safe or vault protection, an outer door and an inner door, each having a bolt-throwing lever adapted to operate in unison, a bail pivotally supported by the outer door and movable into engagement with suitable catches by the movement of the lever of the outer door.

14. In a safe or vault protection, an outer door and an inner door, each provided with

a dial-knob and a bolt-throwing lever, the combination mechanism of the inner door guarding the withdrawal of the bolts of both doors, a connection between the combination-knobs and a connection between the levers, said connections being made when the outer door is closed. 15
